UNITED STATES PATENT OFFICE.

DUNCAN J. FAHLMAN, OF DETROIT, MICHIGAN, ASSIGNOR TO BUHL STAMPING COMPANY, OF DETROIT, MICHIGAN, A CORPORATION OF MICHIGAN.

MILK CAN.

Application filed September 29, 1924. Serial No. 740,548.

This invention relates to sheet-metal containers and relates particularly to milk cans and the like.

In forming milk cans or other vessels requiring frequent thorough cleaning it is highly desirable to avoid the presence of any interior crevices or recesses which may tend to retain dirt or food particles. In securing to the side wall of such a container its bottom or end wall, the resulting interior crevice at the joint has heretofore been filled with solder. The proper soldering of such joints requires skill and considerable time and is hence comparatively expensive.

It is the object of the present invention to apply a prefashioned filler member at the joint between the side and end walls of a sheet metal container and to thereby produce a smooth continuous interior surface less expensively than present methods permit.

It is also an object to utilize such a filler member as a reinforcement for the end of the container to which it is applied.

A further object is to insure against any leakage of liquids past the joint to which said filler member is applied.

These and various other objects the invention attains by the construction herein-after described and illustrated in the accompanying drawing, wherein:

Figure 1 is an axial sectional view of the bottom portion of a milk can or the like, disclosing one embodiment of the invention.

Figure 2 is a similar view showing an alternative construction.

Figure 3 is a similar view showing still another embodiment of the invention.

In these views the reference character A designates the cylindrical side wall of a milk can or other sheet metal container, the bottom or end wall B of which is inserted some distance into said side wall and is formed with a marginal cylindrical flange C projecting toward the adjacent end of the container. The upper portion of said flange is inwardly spaced from the wall A and its lower portion fits snugly within said wall, an annular shoulder C' being formed between said upper and lower portions.

The space above the shoulder C' is occupied by a metal ring D, prefashioned to accurately fill said space. The top face of

said ring is beveled to conform to the incline of the bottom B in case the latter is dished as shown by the drawing, and adjacent said face the ring has an interior annular projection D', forming in effect a fillet the under face of which is rounded to snugly fit the bend resulting from the junction of the bottom B and flange C. The ring D is rigidly connected both to the wall A and to the flange C by spot welding or in some other suitable manner.

While the construction, as so far described, establishes a liquid seal, it is preferred to additionally safeguard the vessel against leakage by an interlock between the walls A and B. Thus the lower edge portion of the wall A is bent to a U-form, as indicated at E, snugly embracing the lower portion of the flange C. Preferably a metal band F is inserted in the lower portion of the flange C, forming a reinforcement for the lower end of the vessel and assisting in maintaining the described interlocking relation of the walls. As shown, the lower edge portion of the band F is outwardly turned beneath the flange C so as to form a supporting base for the vessel. The band F, the flange C, and the U portion E of the wall A are rigidly connected by spot welding or other suitable means.

The construction shown in Figure 2 corresponds to the preceding description except for the use of a heavier reinforcing metal band G. This band is upwardly extended into proximity to the bottom B, its inner face being of constant diameter and its outer face having the annular shoulder G' corresponding to the intermediate shoulder of the flange of the bottom, said band being relatively thick below the shoulder G'.

The construction shown in Figure 3 employs a ring H between the downturned flange I of the bottom of the container and the lower marginal portion of the side wall. In this construction, the flange I has no annular shoulder, being spaced throughout its height from the wall A. The ring H corresponds to the described ring D except that it is substantially coextensive in height with the flange I, snugly filling the entire space between the wall A and said flange, the latter being riveted to said ring and to the wall A as is indicated at J. Preferably the lower portion of the ring H is slightly

thickened forming an exterior annular shoulder K, upon which the wall A seats at its lower edge.

It is characteristic of each of the described constructions that a smooth continuous surface is produced interiorly of the container at the joint between its side and end walls at a reduced expense as compared to present methods, and that the container is strongly reinforced.

What I claim is:

1. A container comprising separate walls and a filler member fitted between said walls and prefashioned to snugly fill the space between said walls and having a face flush with one of said walls interiorly of the container, thereby forming a joint free from crevices.

2. A container comprising separate walls, one of which is bent to overlap the other, and a filler member fitted between said walls and having a surface flush with the interior face of said bent wall, and having a prefashioned projection adjacent said surface rounded to snugly conform to the bend of said wall.

3. A container comprising interlocked walls having spaced portions adjacent their interlock, and a filler member fitted between said spaced portions and prefashioned to snugly fill said space, said member having a face flush with one of said walls interiorly of the container, thereby forming a joint free from crevices.

4. A container comprising an end wall and a separate side wall, the said walls having spaced marginal portions, and a filler ring inserted between said portions and contacting directly with the same to form a joint free from crevices.

5. A container as set forth in claim 4, said ring having a face interiorly flush with said end wall.

6. A container comprising a joined end wall and side wall, marginally interlocked and having spaced portions adjacent their interlock, and a filler ring inserted between said spaced portions and in direct contact with said walls forming a joint free from crevices.

7. A container comprising a cylindrical side wall and a separate end wall having a marginal flange interiorly spaced from said side wall, and a filler ring fitted between and directly contacting with said flange and side wall, and having a face interiorly flush with said end wall.

8. A container comprising a cylindrical side wall and an end wall inserted within said side wall and having an out-turned

flange marginally interlocked with said side wall, the inner portion of said flange being spaced from said side wall, and a filler ring inserted between and directly contacting with the spaced portions of said flange and side wall, thereby forming a joint free from crevices.

9. In a container as set forth in claim 8, a reinforcing metal band fitted within said flange.

10. In a milk can, the combination of a side wall, a separate end wall extending transversely thereof provided with a transversely bent flange extending parallel to said side wall and slightly spaced from the same, and a filler member inserted between said side wall and flange prefashioned to snugly contact directly therewith forming a joint free from crevices.

11. In a milk can, the combination with a cylindrical body, of a separate bottom therefor having a downturned cylindrical flange of a diameter less than the internal diameter of the body to leave an annular space therebetween, and a filler strip between said flange and body, of a cross sectional contour to snugly fit about the bend between said bottom and flange and to also fit the inner face of said body whereby a joint is provided free from crevices.

12. In a milk can, the combination with a cylindrical body, of a separate sheet metal bottom therefor, of concave form having a downturned cylindrical flange forming a rounded corner, said flange being of a diameter slightly less than the internal diameter of the said body, forming a space therebetween, and a filler strip having a cross section prefashioned to snugly fit the space between said cylindrical flange and said body, said filler strip having a rounded portion engaging said rounded corner and having its exposed surface arranged flush with said concave bottom surface forming a continuation of the same.

13. The method of forming milk cans which consists in forming a cylindrical body and a separate sheet metal bottom therefor, having a cylindrical flange of a diameter less than the internal diameter of said body, inserting an annular filler strip between said flange and body, said strip being of cross sectional contour to fit about the bend of said cylindrical flange and forming a joint free from crevices, and securing said flange, body and filler strip together in fixed relationship.

In testimony whereof I affix my signature.
DUNCAN J. FAHLMAN.
